UNITED STATES PATENT OFFICE

155,130

DESIGN FOR A SOUVENIR STICK

Walter Henry Desforges, Sr., and Walter Henry Desforges, Jr., New Orleans, La.

Application September 16, 1947, Serial No. 141,434

Term of patent 14 years

(Cl. D34—5)

To all whom it may concern:

Be it known that we, Walter Henry Desforges, Sr., and Walter Henry Desforges, Jr., citizens of the United States, residing respectively at 611 No. Hennessey Street, in the parish of Orleans and State of Louisiana, and 3232 Dumaine Street, in the parish of Orleans and State of Louisiana, have invented a new, original, and ornamental Design for a Souvenir Stick, of which the following is a specification, reference being made to the accompanying drawing, forming part thereof.

Fig. 1 is a front elevational view of a souvenir stick, showing our new design; and

Fig. 2 is a side elevational view thereof.

The drawing is shaded to indicate color contrast.

We claim:

The ornamental design for a souvenir stick, substantially as shown and described.
